UNITED STATES PATENT OFFICE.

JOHN L. FLANNERY, JR., OF CHICAGO, ILLINOIS, ASSIGNOR TO THE BOYE NEEDLE COMPANY, OF CHICAGO, ILLINOIS, A CORPORATION OF ILLINOIS.

DISPLAY-CABINET.

1,325,238.

Specification of Letters Patent.

Patented Dec. 16, 1919.

Application filed October 3, 1918. Serial No. 256,667.

To all whom it may concern:

Be it known that I, JOHN L. FLANNERY, Jr., a citizen of the United States, residing at Chicago, in the county of Cook and State 5 of Illinois, have invented a new and useful Improvement in Display-Cabinets, of which the following is a specification.

This invention relates particularly to display cabinets adapted to facilitate the storing and sale of small articles of merchandise, such as crochet needles.

The primary object of the invention is to provide a simple and inexpensive cabinet adapted to the purpose of storing small 15 articles of merchandise and facilitating the sale thereof.

The invention is illustrated, in its preferred embodiment, in the accompanying drawing, in which—

20 Figure 1 represents a perspective view of a display cabinet embodying the invention; Fig. 2, a vertical sectional view taken as indicated at line 2 of Fig. 1; Fig. 3, a broken plan sectional view taken as indicated at line 3 of Fig. 2; and Fig. 4, a view of a crochet needle and its sheath, the improved cabinet being especially useful for storing and displaying articles of this character.

In the preferred embodiment, which is 30 illustrated, A represents a casing having a supporting base A¹ adapted to rest on a counter; and B, an inclined tray supported in the casing, and which is preferably removable therefrom.

35 In the illustration given, the casing A comprises the rectangular base A¹; triangular end walls 1 rising therefrom; an inclined wall 2 constituting a fixed cover for the lower front portion of the casing; a 40 swinging rear wall 3 which is connected with the lower rear corners of the end walls 1 by means of pivots 3^a; and a front upper closure 4 which is connected, by hinges 4^a, with the upper edge-portion of the inclined top wall 2, and which is provided with a transparent wall, or window, 4^b, which may be of glass. The casing is provided interiorly with rearwardly and upwardly-inclined guides 5 which are attached to the inner surfaces of the end walls 1, and are adapted to support the tray B in the inclined position.

The tray B, which is removable, comprises two series of elongated compartments, the

front series being designated B¹, and the 55 rear series being designated B². These series are arranged one back of the other and in stepped relation. The tray is constructed with a rear wall 6 and a wall 7 which is parallel thereto and separated 60 therefrom by a space, and separated from the inclined wall 2 of the casing, which is also parallel thereto by a similar space. The compartments are formed by longitudinal partition members 8 and 9, the former being 65 interposed between the walls 6 and 7, and the latter being in front of and attached to the wall 7 and having their free edges adjacent the inner surface of the inclined top member 2 of the casing. The compartments are provided with bottom walls 10, which bear a stepped relation to each other. The tray is furthermore provided with the 70 side walls 11.

The compartments of the series B¹ are 75 open at their front sides and at their upper ends, but when the tray is in position, the inclined wall 2 of the casing affords a front wall for the lower portions of the compartments of this series. The wall 7 affords a 80 front wall for the lower portions of the compartments of the B² series, while the upper ends of these compartments are open and, in effect, the upper portions of the front walls of the compartments of the B² 85 series are cut away.

C designates a crochet needle; and C¹ designates a sheath for the needle. In Fig. 1, a few of the crochet needles are represented in one of the compartments of the front 90 series, and a few crochet needles are represented in the compartment immediately back thereof in the rear series. The crochet needles are arranged with their handle-portions in the lower portions of the compartments, so that their hook-portions are exposed to view by reason of the fact that the front walls of the compartments are, in effect, cut away at their upper portions. This enables the needles to be viewed through 95 the window 4^b, as the needles lie in their compartments. The glass 4^b is provided at its lower portion with a series of numbers D, these numbers running from 1 to 7 and being disposed over the several compartments; also, the glass is provided at its upper portion with a series of numbers D^r, running from 8 to 14, these numbers being placed in 100 105

position to correspond with the compartments of the rear series. These numbers correspond with the numbers designating the sizes of the crochet needles, so that the 5 needles may be arranged in assorted sizes in the tray, thus enabling the salesman to find them readily when a given size is desired by a customer.

The space in the rear lower portion of 10 the casing beneath the tray is divided into compartments 12 and 13, as indicated in Fig. 3. In the compartment 12 are shown a number of sheaths C¹. It is common to provide such sheaths for the hook-portion of the 15 crochet needle, so that when a sale is effected, the needle may be carried readily by the customer. The compartment 12 affords a convenient place for keeping the sheaths.

Access to the needles in the tray may be 20 gained by swinging the closure 4 forwardly about the hinges 4^a. If desired, the rear wall 3 of the casing may be swung rearwardly about the pivots 3^a, thus enabling the tray to be removed from the casing with 25 facility. This enables the tray to be filled conveniently, and re-inserted in the casing. Also, it enables the tray to be removed for the purpose of cleansing, from time to time.

While it is preferred to have the tray re- 30 movable, this is not an indispensable feature. The same may be said with reference to the inclination of the tray. It is desirable that a plurality of series of compartments be em- 35 ployed, and that these series of compart- ments bear a stepped relation to each other, and that they have open front sides at their upper portions. The cabinet described is simple, inexpensive, and well adapted to its purpose.

40 The foregoing detailed description has been given for clearness of understanding only, and no unnecessary limitation should be understood therefrom, but the appended

claims should be construed as broadly as permissible, in view of the prior art.

45

What I regard as new and desire to secure by Letters Patent is:

1. In a display cabinet, the combination of a casing provided with an inclined top wall equipped with a movable closure having a 50 transparent medium therein, and a removable inclined tray disposed back of said inclined wall and having a series of elongated compartments which are open at the front side of their upper portions, said inclined 55 top wall serving as a front wall for the tray.

2. In a display cabinet, the combination of a casing of substantially triangular longitudinal section, said casing having a pivoted rear wall and having an inclined top wall 60 equipped with a pivoted closure provided with a window, and an inclined tray mounted in said casing comprising a plurality of series of elongated rearwardly inclined compartments, said series arranged one partially 65 beneath the other and in stepped relation and said compartments having open front sides at their upper portions and having open upper ends.

3. In a display cabinet, the combination 70 of a casing of triangular longitudinal section, said casing having an inclined top wall equipped with a pivoted closure provided with a window, and a tray in said casing comprising a front series of compartments 75 and a rear series of compartments occupying a stepped relation to each other, the inclined wall of said casing affording a front wall for the lower portions of the compartments of the front series, and the rear wall 80 of the front series of compartments affording a front wall for the lower portions of the rear series, the upper portions of the compartments of the rear series being open at their front sides.

JOHN L. FLANNERY, JR.
